UNITED STATES PATENT OFFICE.

WILLIAM J. POTTER, OF CHICAGO, ILLINOIS.

PROCESS FOR GRAINING AND ORNAMENTAL PAINTING.

Specification forming part of Letters Patent No. 38,412, dated May 5, 1863.

To all whom it may concern:

Be it known that I, WILLIAM J. POTTER, of Chicago, in the county of Cook and State of Illinois, have invented a new and useful improvement in the mode of graining, fresco-painting, and other kinds of ornamental painting; and I do hereby declare that the following is a full, clear, and exact description thereof, reference being had to the accompanying drawing, which form a part of this specification.

In the aforesaid drawing, Figure 1 represents the implement with which the graining and other ornamental painting is produced, consisting of a roller constructed somewhat like that used for inking the type in hand-printing presses.

The nature of my invention consists in the employment of a roller of wood or other suitable material (marked A in the drawings,) whose convex surface is covered or coated with a soft elastic substance which is stamped or impressed with the design of the wood to be imitated, in relief, in the following manner: I first apply a uniform coat of paint of the proper color to the surface which is to be grained or ornamented. I then apply to the said roller a certain liquid compound, herein-after to be described, and pass the said roller over and upon the surface so uniformly painted as aforesaid, and after allowing enough time to elapse to permit the paint to become dry the surface is then rubbed over, and from those portions and spots upon which the said compound was pressed the paint is readily removed, and thus the design to be imitated or grained is effected in this latter method, not by stamping the design upon the surface to be ornamented, but by removing the necessary portion, spots, and lines in a manner similar to the old method.

To enable those skilled in the art to understand and make use of my invention, I will now describe the same with particularity.

In the first place I provide myself with the roller A, constructed substantially as shown in the drawing, and provided with the handle C, whereby it may be operated. A wood engraving is then prepared, representing the imitation of any wood or ornamental design that is required.

The design may be so engraved as to represent those parts which are required to be in

relief upon the roller, by depressions, so that when a cast or impression on the elastic coating of the roller is taken from the engraving it will present the required design in relief; but I consider it a better way to engrave the design, required on the roller, in relief, and to take from this a plaster-cast from which the requisite impression may be molded.

After preparing the wood-engraving or the plaster-cast taken therefrom, as may be preferred, I proceed to prepare the following composition, in which to mold the engraved designs, and which is afterward fixed upon the convex surface of the roller. This composition is prepared as follows: I take one pound of glue and soak the same in water for about two hours. I then add to the glue one pint of molasses, four table-spoonfuls of oil of tar, one ounce of lamp-black, one table-spoonful of olive oil, and one-half of a teaspoonful of soda. I then place this mixture in a can or small vessel, which is then set into a vessel of boiling water and boiled about one and one-half hours, being stirred at intervals during the whole period. After this composition has become partially cooled, it is poured upon the engraving of the design from which the impression is to be molded, enough being used to render the composition of sufficient thickness, (say from one-half to three-fourths of an inch in thickness,) where it remains until perfectly cold, when it becomes solid and elastic. It is then removed, retaining an exact impression of the engraving, and is fixed upon the convex surface of the roller, and is represented by B in the drawing.

The surface to be ornamented is first painted over with a uniform coat of paint of the proper color, and the convex surface of the roller moistened with the following-described liquid compound, the quantity referred to in the description being one-half pint: one part of olive oil, one part of cod-liver oil, one part of oil of almonds, one part of water in which half a tea-spoonful of soda has been dissolved, four tea-spoonfuls of French chalk, twenty drops of the oil of tar, and a little Venetian red or other coloring-matter. Having applied this mixture to the surface of the roller, the latter is then rolled upon the surface to be grained, painted uniformly, as aforesaid, printing or stamping upon the painted surface the design on the roller with the aforesaid compound.

After the paint has had time to dry, the surface is rubbed over, and the paint readily removed from those parts upon which the said compound was painted, leaving the graining or ornamenting accomplished in the most perfect manner.

Where long or large surfaces are to be operated upon, a feeding attachment may be attached to the roller to supply the same with the compound last described, thereby making it unnecessary to remove the roller, greatly facilitating the labor.

I do not confine myself to the particular elastic coating for the roller, which I have described, or the particular compound for taking out the paint, but any suitable material of the

same nature and producing the same effect may be used instead of either or both.

I claim—

The employment, in connection with the aforesaid roller, of some suitable solution, as described, for preventing the drying of the paint forming the figure or ornament, and thereby producing the ornamental design required, by subsequently removing the paint forming such figures in the design, substantially as and for the purposes specified and described.

WILLIAM J. POTTER.
